UNITED STATES PATENT OFFICE.

SIMON O'BRIEN, OF BRISTOL, RHODE ISLAND, ASSIGNOR TO HIMSELF AND
HORATIO P. HOWARD, OF SAME PLACE.

HYDRAULIC MOTOR FOR VESSELS.

SPECIFICATION forming part of Letters Patent No. 286,477, dated October 9, 1883.

Application filed January 26, 1883. (No model.)

To all whom it may concern:

Be it known that I, SIMON O'BRIEN, of Bristol, in the county of Bristol and State of Rhode Island, have invented a new and Improved Motor, of which the following is a full, clear, and exact description.

The object of my invention is to provide a new and improved motor for marine vessels, in which the steam is applied in the most direct way and with very little machinery.

The invention consists in a motor formed of a series of pipes and a cock so connected that water can be drawn in at the bottom of the vessel and forced out at the rear end of the same, whereby the vessel will be moved forward, or water can be drawn in at the rear end of the vessel and forced out at the bottom of the same toward the front end, whereby the vessel will be moved backward.

20 The invention also consists in attaching a hose or flexible pipe to the end of the pipe projecting from the stern, and also attaching the said hose to the rudder, whereby the water issuing from the said hose will assist in steering the vessel.

Reference is to be had to the accompanying drawings, forming a part of this specification, in which similar letters of reference indicate corresponding parts in all the figures.

30 Figure 1 is a longitudinal sectional elevation of a vessel containing my improved motor. Fig. 2 is an enlarged longitudinal sectional elevation of my improved motor. Fig. 3 is a sectional plan view of the same on line $x-x$, Fig. 2.

35 A steam-supply pipe, A, connected with a boiler, B, or with a pipe leading to a boiler, is coupled at its outer end to the casing C of a three-way cock, D, to which casing is attached, at one end, a curved pipe, E, leading into the top of a union-piece, F, that part of the pipe E projecting into the union-piece being contracted. To the other end of the casing C a curved pipe, G, is attached, the outer end of which is attached to and projects into the front end of the union-piece F, the projecting end of the pipe G being also contracted.

To the bottom of the union-piece F a pipe, H, is connected, which extends through the bottom of the vessel and projects toward the front end or bow of the same.

To the rear end of the union-piece F a pipe, J, is coupled, which extends to the stern of the vessel and projects from the same.

To the outer end of the pipe J a flexible pipe or hose, K, is coupled, which is attached to the rudder L. If desired, the said flexible pipe or hose K can be dispensed with. If the vessel is to be propelled forward, the cock D is so adjusted that the steam from the boiler 60 passes directly from the cock D through the pipe G, and is injected through the contracted end of the pipe G into the union F and through the pipe J. The suction thus produced causes water to be drawn through the pipe H into 65 the union-piece F, from which it is forced through the pipe J and out at the rear end of the same at the stern of the vessel. If the vessel is to go straight forward, the rudder is held straight, and the stream of water will be 70 projected from the pipe J in a line parallel to the line of the length of the vessel; but if the vessel is to be turned to one side, the rudder is turned correspondingly, and the stream of water from the pipe J will issue from the end 75 of the same at an angle to the line of the length of the vessel, and thus will assist in turning the vessel. If the vessel is to be moved backward, the three-way cock D is so adjusted that the steam cannot pass from the pipe A 80 through the cock to the pipe G, but passes from the pipe A through the cock D and through the pipe E, and is ejected from the contracted end of the same downward into the union F and pipe H, thus causing a suction of 85 the water through the pipe J, which water passes into the union F and is forced out of the same through the pipe H, the water ejected from the end of the pipe H forcing the vessel 90 backward.

By means of my improved motor the complicated machinery used heretofore can be dispensed with. There is but very little wear and tear, and no grease, oil, packing, &c., are required, and as the steam is applied directly 95 there is no great loss by friction, &c., as in other machinery.

Having thus fully described my invention, I claim as new and desire to secure by Letters Patent—

1. In a motor, the combination, with the steam-supply pipe A, of the three-way cock D,

the pipe E, extending into the top of the union-piece F, the pipe G, extending into the front end of the same, the pipe H, coupled to the bottom of the union and extending to and projecting from the bottom of the vessel toward the front end of the same, and of the pipe J, attached to the rear end of the union-piece and extending to the stern of the vessel, substantially as herein shown and described, 10 and for the purpose set forth.

2. In a motor, the combination, with a vessel, of the pipe J, extending to the stern of the vessel, and through which pipe water can be ejected, of the flexible pipe or hose K, attached 15 to the end of the pipe J, and attached to the rudder L, substantially as herein shown and described, and for the purpose set forth.

3. In a motor, the combination, with the

boiler B, of the pipe A, the three-way cock D, the pipe E, projecting into the top of the union-piece F, the pipe G, projecting into the front end of the union-piece, the pipe H, coupled to the bottom of the union-piece and projecting from the bottom of the vessel toward the front end of the same, the pipe J, coupled to the 20 rear end of the union-piece and extending to the stern of the vessel, and of the flexible pipe or hose K, attached to the end of the pipe J, and of the rudder L, substantially as herein shown and described, and for the purpose set 25 forth.

SIMON O'BRIEN.
